DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

PHOTOCODUCTIVE COMPOSITIONS AND ELEMENTS

Rein Virkhaus, 1/2 Eastman Kodak Co., Kodak Park
Division, 1669 Lake Ave., Rochester, N.Y. 14650

Filed Dec. 20, 1971, Ser. No. 110,129

Int. Cl. G03g 5/06

U.S. Cl. 96—1.5

No Drawing. 21 Pages Specification
Photoconductive ylid compounds having the formula:

wherein R₁ and R₂ are each an alkyl radical, an alkoxy radical, an aryl radical, a cyano radical, a halogen atom or a hydrogen atom; Ar₁, Ar₂ and Ar₃ are each aryl radicals; and Z is a Group Va element, are useful in electrographic elements. Useful elements are comprised of a conductive support having thereon a layer of a photoconductive composition comprised of an electrically insulating, film-forming organic binder and an ylid compound of the above formula.
